LÉON DUFOUR, OF VERSOIX, NEAR GENEVE, SWITZERLAND

ROTARY TILLER

Application filed August 12, 1931, Serial No. 556,639, and in Germany August 14, 1930.

In rotary tillers with resiliently yielding tines it is known to obtain the desired resiliency by using as stems for the actual tines wound springs which are arranged or distributed around the driving shaft.

The present invention relates to a rotary tiller with tines secured upon the driving shaft by intervening helical or spiral springs wound around the driving shaft itself, having preferably their turns side by side, in which the springs are so arranged on the shaft, that during normal working their inner surface is not applied to the shaft when they yield backwardly during the bite, but if the normal resistance is exceeded, they yield backwardly and inwardly and wind close upon the shaft (which is not necessarily round) as a safeguard against breakage. Further deformation of the springs by distortion in the direction of the pull (of stones, roots or like) is thus made impossible, while the arm at which the resulting bending moment acts is substantially diminished so considerably relieving the springs.

With this construction the yield rearward with respect to the direction of cut may be kept very great while the inward yield may be smaller than when the center of rotation of the spring is outside the shaft.

By winding the springs around the driving shaft and so dispensing with eccentrically arranged link springs so much room is set free for enlarging the working hook or tine that for a given speed of cut the bite is accompanied by less burrowing and at moderate speeds of cut a larger bite can be taken than otherwise. By this means coarser breaking up of the earth is obtained suitable to field cultivation as distinct from garden cultivation.

In the accompanying drawings various examples of construction according to the invention are illustrated employing in some cases round steel springs and in others flat springs.

Figure 1 is a partial cross section through one embodiment, with round steel springs;

Figure 2 shows a detail section on line A—B of Figure 1;

Figure 3 shows a longitudinal section on line C—D of Figure 1;

Figure 4 represents an embodiment with flat steel springs;

Figure 5 is a detail view of a device for fastening the tines to such flat springs;

Figures 6 and 7 show an alternative form for the tools;

Figure 8 shows a diametrical arrangement of tines;

Figure 9 shows a method of fastening several symmetrical double springs on the shaft.

Figure 10 is a detail view of the fastening of flat springs.

In Figures 1, 2 and 3 which illustrate one such construction, a round steel spring *b* is so wound around the driving shaft *a* with its turns side by side that when stressed by normal working the greater part of its springy length stands away from the shaft, and only when the tool encounters some unusual resistance in the earth does the spring wind close upon the shaft *a* so as not to be deformed and so as simultaneously to shorten the arm at which the bending moment then applied to the tool acts. The spring *b* is constructed in known manner as a double spring with its two parts mutually inclined or symmetrically wound from the centre outward to each side. At the ends *b*¹ by which the double spring is fastened to the shaft, recesses *c* are formed in said ends which enable these ends to be sprung by great axial pressure under low hooks *d* projecting from the shaft. No further fastening of the springs is necessary. The double spring can be passed over the shaft from one end and over the hooks *d*, if its proportions and its material are suitably chosen so that the radial play between the shaft and the turns of the spring is greater than the radial projection of the hooks.

The claws *i* of round steel may be connected with such double springs of known patterns after the fashion of a knot and the claws may be either simple or forked. For this purpose in either case the end of the claw *i* to be attached to the stem is formed into a loop *i*¹ which is laid flat against the correspondingly looped limb *b*² of the double spring. A key *m* is inserted through the loops and they are surrounded and held to-

gether by a metal casing *k* sprung over them. The key *m* prevents the loops being thrust one past the other, so that the casing *k* has only to take lateral and rearward bending moments and to hold itself resiliently in working position while the key *m* takes the actual pull of the tool.

To give the claws and springs yet greater inward yield before the latter become applied to the shaft, the springs may be wound of flat steel, which, owing to the form in which it is wound and notwithstanding its greater width, allows considerable lateral yield in addition to rearward and inward yield so that the claws can be deflected laterally by stones. These flat springs also permit the very simple arrangement of several tines in one and the same plane transverse to the shaft. Such a construction is shown in Figure 4 where the flat springs *b* have at their inner ends claws *b*² engaging in longitudinal slots *o* in the shaft *a*. They may conveniently be held down upon the shaft by hooks *d* being reinforced if desired as shown in Figure 10 by a blade *q* which has edge ribs engaging beneath the hooks. The springs are thus protected against twisting and bending at the point of fastening, and also are interchangeable with the round steel springs of Figures 1, 2 and 3.

If two (or more) flat springs are used in the same transverse plane, as in this instance, the spirals of several turns are so interleaved that when one tool yields rearwardly and its spring yields rearwardly and inwardly it comes upon and transfers some stress to the next spring. Thus the springs of the tines which are not at the moment biting are also stressed and in an extreme case will all wrap themselves close upon the shaft and so preserve themselves from fracture.

The connection between the flat springs and the claws *i* is preferably made by means of a wedge lock *s* (Figure 5). The root *i*² of the claw *i* is formed into a loop and placed on the inner side of the outer end of the spring between converging retaining flanges *b*⁴ formed upon the spring. Into these the loop *i*² wedges and the working pressure tends to secure it more firmly in place. This connection may be used for both simple and forked claws.

While in the construction above described the actual tool consists of a claw or bent hook laterally bent flat steel claws *j* may be used instead. Such claws are shown in Figures 6 and 7 and they are better than the usual forwardly bent claws for cutting off weeds and stubble; and when they are inclined backward their cutting edges are not so much caught up as the other claws by roots or stones, nor do they collect weeds so much. To fasten such claws upon the flat springs the outer ends of the springs are bent to form a short claw *b*⁵ like that at their inner ends,

while the inner end of the flat steel claw *j* is bent round them in a flat loop which is sprung over the snaps down upon the claw end of the spring and is prevented by a shoulder or like projection from pushing further along the spring.

If it is desired when using round steel spiral springs to place two claws not one beside the other but about 180° apart without interleaving the springs, a single spring may be prolonged in an arc of about 180° beyond the point at which its tool is fastened to it. This is shown in Figure 8. A fastening *t* intermediate in the length of the spring attaches one tool and a similar fastening *t*¹ at its end attaches the other.

Figure 9 shows a way of fastening several symmetrical double springs upon the driving shaft *a* so that the claws are staggered circumferentially by about 180°. The fastening is effected by means of bushes *u* keyed upon the shaft *a*, each of which is provided at one end with two oppositely directed hooks *d*¹. The ends of each double spring are engaged by the hooks of two neighbouring bushes *u*, so that for instance the left hand end of the left hand spring in Figure 9 is engaged in the hook of the left hand bush and its right hand end in the lower hook of the next bush, the upper hook of which serves for fastening the left hand end of the second spring, and so on. This method of fastening by means of separate bushes facilitates the mounting of the springs upon the shaft.

What I claim is:

1. A rotary tiller comprising a driving shaft, working tines and springs securing the working tines to the driving shaft, said springs being wound around the driving shaft itself and being so formed relatively to the same that under the normal working stresses the greater part of the resilient length of the turns of the springs stands out from the shaft permitting the tool to yield rearwardly, while when an abnormal resistance is encountered in the ground the springs wind close upon the circular or other shaft and diminish the arm at which the bending moment then arising acts so as to avoid deformation or fracture of the springs.

2. A rotary tiller comprising a driving shaft, working tines and springs securing the working tines to the driving shaft, said springs being wound around the driving shaft itself and being so formed relatively to the same that under the normal working stresses the greater part of the resilient length of the turns of the springs stands out from the shaft permitting the tool to yield rearwardly, while when an abnormal resistance is encountered in the ground the springs wind close upon the circular or other shaft, said springs consisting of symmetrical double springs of round steel having their

ends sprung under hooks upon the shaft and being recessed to engage upon said hooks.

3. A rotary tiller comprising a driving shaft, working tines and springs securing the

5 working tines to the driving shaft, said springs being wound around the driving shaft itself and being so formed relatively to the same that under the normal working stresses the greater part of the resilient length of the 10 turns of the springs stands out from the shaft permitting the tool to yield rearwardly, while when an abnormal resistance is encountered in the ground the springs wind close upon the circular or other shaft, said 15 springs having their turns lying side by side.

4. A rotary tiller comprising a driving shaft, working tines and springs securing the working tines to the driving shaft, said springs being wound around the driving 20 shaft itself and being so formed relatively to the same that under the normal working stresses the greater part of the resilient length of the turns of the springs stands out from the shaft permitting the tool to yield rearwardly, while when an abnormal resistance is encountered in the ground the springs wind close upon the circular or other shaft, the tines being connected to the springs by 25 means of loops formed on the spring and tool which are coupled by a key passing through them and held together by a surrounding resilient casing.

5. A rotary tiller comprising a driving shaft, working tines and springs securing the 35 working tines to the driving shaft, said springs being wound around the driving shaft itself and being so formed relatively to the same that under the normal working stresses the greater part of the resilient 40 length of the turns of the springs stands out from the shaft permitting the tool to yield rearwardly, while when an abnormal resistance is encountered in the ground the springs wind close upon the circular or other shaft, said springs consisting of flat steel springs 45 having at their outer end converging flanges, whilst the tines are provided at their root with a wedge shaped end arranged to wedge between said converging flanges of the 50 spring.

6. A rotary tiller comprising a driving shaft, working tines and springs securing the working tines to the driving shaft, said 55 springs being wound around the driving shaft itself and being so formed relatively to the same that under the normal working stresses the greater part of the resilient 60 length of the turns of the springs stands out from the shaft permitting the tool to yield rearwardly, while when an abnormal resistance is encountered in the ground the springs wind close upon the circular or other shaft, said springs being constituted by several 65 symmetrical double springs secured one beside the other on the driving shaft and car-

rying the tines in circumferentially staggered position, the end of each spring being fastened by hooks formed on two neighbouring bushes fixed upon the shaft.

In witness whereof I have hereunto signed 70 my name this 3rd day of August, 1931.
